DOOR

Jacinto Esteban y Bartolome, Madrid, Spain, assignor to
Esteban y Bartolome-Industrias de la Madera S.A.,
Madrid, Spain

Filed May 18, 1967, Ser. No. 7,179

Claims priority, application Spain Dec. 24, 1966

Term of patent 14 years

(Cl. D13—1)

FIG. 1

FIG. 2

FIGURE 1 shows the front face of the door, the rear face of the door shows the same design as the front face as shown; and

FIGURE 2 is a view of one vertical side edge of the door, the other corresponding side edge being identical.

The bottom edge of the door is planar and the top edge is similar to the side edges.

I claim:

The ornamental design for a door, as shown and described.
